UNITED STATES PATENT OFFICE.

WILFRED T. BIRDSALL, OF MONTCLAIR, NEW JERSEY, ASSIGNOR, BY MESNE ASSIGNMENTS, TO WESTINGHOUSE LAMP COMPANY, A CORPORATION OF PENNSYLVANIA.

VACUUM-TYPE CONVERTER.

1,388,793.

Specification of Letters Patent. Patented Aug. 23, 1921.

Application filed January 5, 1917. Serial No. 140,740.

To all whom it may concern:

Be it known that I, WILFRED T. BIRDSALL, a citizen of the United States, and a resident of Montclair, in the county of Essex and 5 State of New Jersey, have invented a new and useful Improvement in Vacuum-Type Converters, of which the following is a specification.

My invention relates to vacuum-type electric apparatus of the character wherein the discharge is maintained by virtue of electron emission, and it has for its object to provide apparatus of the character designated which shall operate effectively in the absence of 15 auxiliary means for maintaining one or more electrodes at an electron-emitting temperature.

Another object of my invention is to provide apparatus of the character designated 20 which shall operate, with stability and efficiency, as a lamp, as a converter, or in other fields of application of apparatus of the general character indicated.

In the accompanying drawing, Figure 1 is 25 a side view, partially diagrammatic, of a piece of vacuum-type electric apparatus embodying one form of my invention, and Figs. 2 and 3 are similar views of modifications of the apparatus shown in Fig. 1.

30 It is well known that current flow may be produced and maintained through a highly evacuated space by placing therein an anode and a cathode and by maintaining said cathode at a high temperature. The hot 35 cathode produces electronic emission and the electrons travel to the anode, permitting current flow in the opposite direction.

It has been customary, in the past, to provide a cathode in the form of a filament and 40 to pass auxiliary heating current through said filament to render said cathode an electron source. This type of apparatus is illustrated in the well known Fleming rectifier and in the De Forest audion, both widely 45 used in wireless telegraphy and telephony.

It is obviously troublesome and expensive to maintain an auxiliary current source for supplying heating current to the cathode and I have found that, by properly designing 50 a cathode with respect to its heat-dissipating properties, sufficient heat may be derived from the main current flow, when once initiated, to maintain the cathode thereafter at an electron-emitting temperature.

55 Not only am I able to provide apparatus,

of the character just described, for operation on direct current, where the heat-producing action of the main discharge at the cathode is continuous, but I also find that operation is possible upon alternating current, where 60 the heating effect of the main discharge is discontinuous. In apparatus of this character, two similar electrodes may be provided, said electrodes being connected, respectively, to the terminals of the alternating-current 65 source and each being preferably provided with auxiliary heating means. With this form of apparatus, both electrodes are raised to an electron-emitting temperature, whereupon bilateral current flow takes place therebetween, and discontinuous heating effects are produced at both electrodes, each electrode functioning alternately as an anode 70 and as a cathode. The heat-dissipating properties of each electrode are so adjusted 75 that the heat is conserved during periods of deficiency in the heating effect of the main discharge, thus maintaining each electrode at all times, during operation, at an electron-emitting temperature.

80 In all forms of vacuum-electric apparatus, there is a tendency for the discharge to localize upon restricted portions of the electrode area, producing excessive heating thereof and consequent destruction of the 85 electrode. I find that this action may be effectively prevented by associating suitable conducting shields with each electrode and by maintaining said shields at a relatively 90 low temperature while imparting thereto a charge similar to that of the associated electrode. In this way, an electrostatic effect is produced upon the discharge, causing it to spread out more or less uniformly over the 95 entire surface of the electrode. At the same time, the relatively low temperature of said shielding members prevents them from becoming centers of electron emission and, therefore, prevents the flow of the discharge thereto.

100 Other forms and phases of operation of my invention will hereinafter more fully appear.

Referring to Fig. 1 of the drawing for a more detailed understanding of my invention, I show a highly evacuated container 105 composed of glass or any other suitable material at 7. Said container is provided with two electrodes 8 and 9, each of which is shown as a coiled filament, although, in this 110

- particular case, one of said electrodes may take the form of a tungsten or carbon body, as is usual in vacuum-converter practice. The filamentary electrode 8 is mounted between two leading-in wires 10 and 11, and a source of heating current, such, for example, as a battery 12, is connected between said leading-in wires through an adjustable resistor 13 and a switch 14.
- 10 In like manner, the filamentary electrode 9 is mounted between leading-in wires 15 and 16 and may be provided with heating current from a source 17 through a resistor 18 and a switch 19. A main source of direct current, such, for example, as a battery 20, is connected between the leading-in wires 10 and 15 through a suitable switch 21.
- 15 The leading-in wires 10, 11, 15 and 16 are each extended a short distance beyond the associated electrodes, as shown at 22—22, for a purpose to be hereinafter more fully pointed out.
- 20 Having thus described the arrangement of apparatus embodying my invention, the operation is as follows: At the outset, the switches 14 and 19 are both closed and the resistors 13 and 18 are adjusted to bring the electrodes 8 and 9 to a suitable electron-emitting temperature. The switch 21 is then 25 closed, permitting current flow from the electrode 9, as an anode, to the electrode 8, as a cathode. The switches 14 and 19 may now be opened, whereupon the electrode 8 continues to function as a source of electron- 30 emission, the temperature thereof being maintained by said current flow and the current flow, in turn, depending upon the electron emission. The tendency of the discharge to localize upon restricted portions 35 of the electrodes 8 and 9 is largely eliminated by the electrostatic influence of the shielding horns 22—22. Said horns remain comparatively cool because of their relatively large radiating surface, preventing 40 the flow of electrons therefrom and the consequent flow of current thereto. The main portions of the electrodes 8 and 9, on the other hand, are centrally disposed within the container and have relatively poor heat- 45 dissipating properties, thus enabling such electrode portions to maintain a high temperature and an electron-emitting state. Operation may now be continued indefinitely 50 without further use of the auxiliary heating sources 12 and 17. Referring to the form of apparatus shown in Fig. 2, a container 7, similar to that shown in Fig. 1, is provided with similar anodes 8 and 9 mounted between leading-in wires 10—11 and 15—16.
- 55 The energy for the operation of the device is derived from a source of alternating current, however, such, for example, as the secondary winding 23 of a transformer 24, the terminals of said secondary winding being 60 connected respectively to the leading-in wires 11 and 16. The remaining leading-in wires 10 and 15 may be connected together through a resistor 25 and a switch 26.
- To start the device of Fig. 2, the switch 26 is first closed, whereupon alternating current traverses the filaments 8 and 9 and the resistor 25, rapidly raising said filaments to an electron-emitting temperature. The switch 26 is now opened, whereupon a bilateral discharge takes place between the 70 electrodes 8 and 9, the heat generated in each electrode during its periods of anodic activity, combined with that generated during its periods of cathodic activity, being sufficient to maintain an electron-emitting temperature over the periodic intervals of deficiency in the heating effect of the alternating current.
- 75 Both of the above described figures embody apparatus of bilateral conductivity 85 particularly adapted for electric lighting but, obviously, my invention is susceptible of application in connection with converting or rectifying apparatus either of the half wave or single-anode type wherein the cathode must maintain its temperature during intervening half waves or of the full wave or double-anode type wherein the cathode must maintain its temperature only at such times as the back electromotive force of 90 the load and of the converting arc exceeds the instantaneous electromotive force of the 95 alternating-current supply.
- Having thus described the apparatus of the latter type is indicated in Fig. 3 comprising a central condensing 100 chamber 28 provided with laterally and outwardly extending arms 29 and 30. Anodes 31 and 32 of any suitable type, such, for example, as flat disks of refractory material are mounted in the upper portions of the 105 arms 29 and 30, respectively, and are connected to a supply winding 23. A cathode 33 of the hot filament type, is mounted in the lower portion of the chamber 28 and may be raised to an electron-emitting temperature by current from an auxiliary battery 20 through a switch 21. The cathode 33 is connected to the mid point of the supply winding 23 through a suitable load 34. In operation, the switch 21 is first closed, 110 causing heating current to flow through the cathode 33 and raising the same to an electron-emitting temperature. Load current flows from the anodes 31 and 32 alternately and flows to the cathode before the 115 substantially pure electron stream. The switch 21 may now be opened and the rapidly recurring impulses of load current flowing to the cathode 33 maintain it at such a temperature that sufficient electrons are 120 continuously given off thereby.
- 125 While I have shown my invention in a plurality of different forms, it will be obvious to those skilled in the art that it is susceptible of various other modifications 130

without departing from the spirit thereof and I desire, therefore, that only such limitations shall be placed thereupon as are imposed by the prior art or as are set forth 5 in the appended claims.

I claim as my invention:

1. In an electron tube, the combination with two leading-in wires, of a filamentary cathode mounted therebetween, means for 10 supplying current to said cathode for the production of electron emission thereat, an anode mounted within said tube, said leading-in wires extending beyond said cathode in the general direction of said anode, and 15 means for maintaining an electromotive force between said cathode and said anode, said leading-in wire extensions being mounted in such relation to said cathode and having such conducting properties as to 20 fail to become the seats of active electron emission.

2. In vacuum-type electric apparatus, the combination with two filamentary electrodes, of means for connecting a source of alternating-current thereto, means for initially 25 passing heating current through each of

said electrodes to produce an electron-emitting temperature therein, whereby bilateral current flow is established therebetween, the heat-dissipating properties of said electrodes being so adjusted that they are thereafter maintained at an electron-emitting temperature solely by said bilateral current flow, and means for substantially preventing the localization of said discharge upon restricted portions of the surface of either of 30 35 said electrodes.

3. In vacuum-type electric apparatus, the combination with two filamentary electrodes, of means for connecting a source of alternating-current thereto, means for initially passing heating current through each of 40 45 said electrodes to produce an electron-emitting temperature therein, and electrostatic shielding means for substantially preventing the localization of said discharge upon restricted portions of the surface of either of said electrodes.

In testimony whereof, I have hereunto subscribed my name this 23rd day of December, 1916.

WILFRED T. BIRDSALL.
